C. S. ACKLEY

DEVICE FOR PLACING WAVES IN HAIR

Filed Dec. 30, 1926

UNITED STATES PATENT OFFICE.

CHARLES S. ACKLEY, OF BROOKLYN, NEW YORK.

DEVICE FOR PLACING WAVES IN HAIR.

Application filed December 30, 1926. Serial No. 157,914.

This invention relates to a device for producing or placing waves in hair.

Various forms of heating devices or rods have been devised for placing waves in hair. In order to produce a lasting wave, the hair must be wound very tightly around the heating rod or tube and must be securely held thereon.

In carrying out the usual method of so-called "permanent" waving, a plurality of strands of hair are first tied together close to the scalp. The tied strands are then secured to one end of the curling or heating tube or rod by tying the grouped strands thereto and the strands are then wound tightly around the rod and the ends are tied to the rod. A moistened strip of felt or absorbent material is then wound around the hair and this material is tied.

It will be evident that the carrying out of the method just outlined requires a considerable amount of time and when it is considered that the operation outlined must be repeated for thirty or forty different groups of strands on one head, the time expenditure is exceedingly great.

This invention has for its salient object to provide a device of the character specified so constructed and arranged that its use will cut down very materially and to a minimum, the time required to produce or place waves in hair.

Another object of the invention is to provide a device of the character specified having means for quickly securing and tightly winding hair on the curling rod or tube.

Another object of the invention is to provide a device of the character specified so constructed that the hot portions of the device will be insulated from and cannot contact with the scalp of the person whose hair is being waved.

Another object of the invention is to provide a device of the character specified so constructed that the hair can be quickly secured thereto or released therefrom.

Another object of the invention is to provide a device of the character specified having a non-metallic sheath or tube on which the hair is wound.

Another object of the invention is to pro-

vide a device of the character specified so constructed that the heating element is entirely enclosed by non-metallic insulating means adapted to insulate both as to heat and electricity.

Further objects of the invention will appear from the following specification taken in connection with the drawings, which form a part of this application, and in which

Fig. 1 is an elevational view of a device constructed in accordance with the invention;

Fig. 2 is an enlarged elevation partly in section showing the details of construction of the device shown in Fig. 1;

Fig. 3 is a detail sectional elevation on an enlarged scale taken substantially on line 3-3 of Fig. 2;

Fig. 4 is an elevational view showing the construction and mounting of the clip at the free end of the device;

Fig. 5 is an elevational view of the spring which prevents rotation of the clip support in one direction and permits rotation thereof in the opposite direction;

Fig. 6 is an end elevation of the plug at the free end of the heating tube or sleeve;

Fig. 7 is a sectional elevation taken substantially on line 7-7 of Fig. 4;

Fig. 8 is a sectional elevation taken substantially on line 8-8 of Fig. 2;

Fig. 9 is an elevational view of the slideable clip; and

Fig. 10 is an elevational view showing a plurality of strands of hair wound on the device.

The invention briefly described consists of a device comprising an elongated sheath or tube within which is enclosed a heating element. The sheath is preferably formed of non-metallic insulating material and the ends of the sheath are closed by material of similar nature. The heating element is preferably surrounded by a tube having a covering of absorbent material and the outer sheath is preferably spaced from the absorbent covering and perforated.

The cover or plug at one end of the sheath has terminals for the heating element and the closure at the other end of the sheath has

an extension of insulating material, such as cork, to prevent the device from contacting with the scalp of the person whose hair is being waved. A clip is provided at one end 5 of the tube for securing a plurality of strands of hair thereto and this clip is mounted on a support which is rotatable in one direction but is held against rotation in the opposite direction. The free ends of the 10 strands of hair are secured by another clip which is slidably mounted on the sheath or tube. The support for the slidable clip is non-rotatably mounted.

Further details of the invention will appear 15 from the following description.

In the particular form of the invention illustrated, the device comprises a heating element 20 preferably wound on a core 21 of suitable insulating material, such as asbestos 20 and surrounded by an insulating sheath 22 of similar material. The heating element is enclosed within but insulated from a tube 23 which may be formed of metal or other suitable material.

25 One end of the tube 23 has secured thereto a plug 25 which carries the terminals 26 and 27 for the heating element. The member 25 is preferably formed of non-metallic insulating material.

30 The tube 23 preferably has a covering 30 of absorbent material, such as asbestos, and the tube and covering are surrounded by an elongated sheath or sleeve 31 which is perforated as shown at 32. The sheath is preferably formed of insulating material, such as porcelain or bakelite, and spaced from the covering 30 as clearly shown in Fig. 2.

One end of the sheath 31 abuts on a conical end portion 33 of the plug 25 and the 40 other end is supported by a conical portion 35 of a plug 36 formed of suitable insulating non-metallic material. The plug 36 is threaded on the end of the tube 23 and the sheath or sleeve 31 is securely held between 45 the plugs 25 and 36.

A projection 40 formed of cork or other suitable insulating material is secured to a reduced portion 37 of the plug 36, a washer 41 being mounted on the reduced portion 37 50 and acting as a spacer between the projection and the plug.

Means is carried by the plug 36 for securing a plurality of strands of hair to the device. The plug as shown in Figs. 2 and 6 55 has a cylindrical portion 45 having a notch 46 formed therein. A spring 47 is mounted on the portion 45 and has an inturned end 48 positioned in the notch 46. The opposite end 49 of the spring is bent outwardly to a slight extent and exerts an outward pressure.

A ring 50 is mounted on the outer surface of the spring 47 and has its inner annular surface corrugated or provided with a plurality of notches 51. The ring has a pair of lugs 55 and 56 secured to its outer surface

and forming a support for a pivot 57 of a clip 58. The ring also has formed thereon a second pair of lugs 60 and 61 which are bent inwardly as shown in Fig. 7 and are adapted to engage the end portion 62 of the clip 58 70 and hold the clip and the hair clamped thereby.

The sheath or sleeve 31 is preferably formed with a slightly irregular shape and the sleeve has slidably mounted thereon a 75 ring 66 having an offset portion 67 corresponding to the offset portion 65 in the sleeve. In other words, the ring and sleeve are similar in contour. The ring 66 is, therefore, slidable longitudinally on the sleeve but is 80 held from rotation with respect thereto. The ring 66 has lugs 68 which form a support for the pivot 69 of a clip 70 similar in construction to the clip 58. The ring 68 also has a pair of lugs 71 and 72 which coact to secure 85 the clip in the same manner as the lugs 60 and 61.

The device is used in the following manner. It is first dipped in water or some other suitable solution, thereby saturating 90 the absorbent covering 30 around the tube 23.

Then as shown particularly in Fig. 10, a plurality of strands of hair is separated from the remaining hair and is placed beneath the clip 58 with the cork or insulating projection 40 as close to the scalp as possible. The strands are then wound in a spiral around the perforated sleeve or sheath 31, the length of the sheath covered depending on the 95 length of the hair. When the hair has all been wound on the sheath, the ring 66 is moved longitudinally on the sheath to the ends of the strands and these ends are then placed beneath the clip 70.

100 After this has been done, the ring 50 having mounted thereon the clip 58 is held by the fingers of the operator or user and the sleeve 31 and parts affixed thereto and carried thereby are rotated in an anti-clockwise direction, viewing Fig. 3, until the hair is wound as tightly as possible around the sheath 31.

105 From the foregoing description it will be evident that the use of the device described will eliminate many operations which are now necessary to place waves in hair. For instance, as outlined at the beginning of the specification, the method now used requires four different tying operations 110 whereas the method above described can be carried out with the device described without any tying operations, the use of the two clips entirely eliminating these steps. Furthermore, the hair can be wound more 115 tightly around the sheath by means of the connection between the mounting for the clip 58 and the plug 36.

120 It will be understood that the heat generated by the heating element will cause the 130

moisture from the absorbent covering 30 to pass outwardly through the perforations of the sleeve or sheath 31 and through the hair, thus dissipating the moisture and drying the hair.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

15. What I claim is:

1. A hair waving device comprising a sleeve, means for heating the sleeve, and means on said sleeve for securing the hair to the sleeve, said means including a member pivoted on an axis parallel to the axis of the sleeve and being rotatable in one direction around the axis of the sleeve.

2. A hair waving device comprising a sleeve, means for heating the sleeve, and means on said sleeve for securing the hair to the sleeve, said means including a ring rotatable in one direction around the sleeve axis and held against reverse rotation, and a clip mounted on said ring.

3. A hair waving device comprising a sleeve, means for heating the sleeve, and means on said sleeve for securing the hair to the sleeve, said means including a ring rotatable in one direction around the sleeve axis and held against reverse rotation, and a clip pivotally mounted on said ring.

4. A hair waving device comprising a sleeve, means for heating the sleeve, and means on said sleeve for securing the hair to the sleeve, said means including a ring rotatable in one direction around the sleeve axis and held against reverse rotation, and a clip pivotally mounted on said ring on an axis substantially parallel to the sleeve axis.

45. 5. A hair waving device comprising an elongated sheath, means for heating said sheath, a clip at one end of the sheath for securing hair thereto, and a clip slidably mounted on said sheath.

50. 6. A hair waving device comprising an elongated sheath, means for heating said sheath, a pivoted clip at one end of the sheath for securing hair thereto, and a pivoted clip slidably mounted on said sheath.

55. 7. A hair waving device comprising an elongated sheath, means for heating said sheath, a ring mounted to rotate around the axis of the sheath, means for preventing rotation of said ring in one direction, and means carried by said ring for securing hair thereto.

8. A hair waving device comprising an elongated sheath, means for heating said sheath, a ring mounted to rotate around the axis of the sheath, resilient means for pre-

venting rotation of said ring in one direction, and means carried by said ring for securing hair thereto.

9. A hair waving device comprising an elongated sheath, means for heating said sheath, a ring mounted to rotate around the axis of the sheath, means for preventing rotation of said ring in one direction, and means pivotally carried by said ring for securing hair thereto.

10. A hair waving device comprising an elongated sheath, means for heating said sheath, a ring mounted to rotate around the axis of the sheath, means for preventing rotation of said ring in one direction, means carried by said ring for securing hair thereto, a second ring slidably but non-rotatably mounted on said sheath, and hair securing means carried by said second ring.

11. A hair waving device comprising an elongated sheath, means for heating said sheath, a ring mounted to rotate around the axis of the sheath, means for preventing rotation of said ring in one direction, means carried by said ring for securing hair thereto, a second ring slidably but non-rotatably mounted on said sheath, and hair securing means pivotally carried by said second ring.

12. A hair waving device comprising a sleeve, means for heating the sleeve, hair securing means at one end of the sleeve, said means being rotatable in one direction only, and hair securing means slidably but non-rotatably carried by said sleeve.

13. A hair waving device comprising a tubular, non-metallic curling element adapted to receive thereon a coil of hair, a heating element disposed within said curling element, and non-metallic members at the ends of the curling element enclosing the heating element therein.

14. A hair waving device comprising a perforated, tubular, non-metallic curling element adapted to receive thereon a coil of hair, a heating element disposed within said curling element, and non-metallic members at the ends of the curling element enclosing the heating element therein.

15. A hair waving device comprising a tubular, non-metallic curling element adapted to receive thereon a coil of hair, a heating element disposed within said curling element and spaced therefrom, and non-metallic members at the ends of the curling element enclosing the heating element therein.

16. A hair waving device comprising a non-metallic, tubular curling element adapted to receive thereon a coil of hair, a heating element disposed within said curling element and insulated therefrom, a plug at one end of the curling element having contact terminals connected to the heating element.

17. A hair waving device comprising a heating element, a curling tube surrounding said element and adapted to receive thereon

a coil of hair, said tube having an absorbent covering thereon and a perforated, non-metallic sleeve surrounding and spaced from said tube and covering.

5 18. A hair waving device comprising a tubular curling element, means within said curling element for heating said element, and means on the curling element for securing the hair thereto, said securing means being mounted on the curling element for rotation in one direction.

10 19. A hair waving device comprising a perforated, tubular curling element adapted to receive thereon a coil of hair to be curled, means within said element for heating the curling element, and means mounted on said curling element and disposed at one end thereof for securing the coil of hair thereto, said securing means being mounted for rotation in one direction.

15 20. A hair waving device comprising a tubular curling element adapted to receive a coil of hair to be curled, means within said element for heating the element, and means 20 mounted on the curling element for securing the coil of hair thereto, said securing means

including a member pivoted on an axis parallel to the axis of the curling element.

21. A hair waving device comprising a tubular curling element, means disposed 30 within said element for heating the curling element, and means mounted on the curling element for securing a coil of hair thereto, said securing means including a member pivoted on an axis parallel to the axis of the 35 curling element and being rotatable bodily around said axis.

22. A hair waving device comprising a tubular curling element formed of non-metallic material, a heating element disposed 40 within and insulated from and spaced from the curling element, an insulating plug secured at each end of the sleeve and closing the ends thereof, terminals for the heating element carried by one of said plugs and 45 connected to the heating element and heat insulating means secured to and extending beyond the other plug.

In witness whereof, I have hereunto set my hand this 27th day of December, 1926.

CHARLES S. ACKLEY.
